UNITED STATES PATENT OFFICE.

ARNOŠT FISCHMANN, OF PRAGUE, CZECHOSLOVAKIA, ASSIGNOR TO ALFRED DONE-
BAUER, OF PRAGUE, CZECHOSLOVAKIA.

SUPPORT FOR JEWELRY.

Application filed February 29, 1928, Serial No. 258,036, and in Germany February 6, 1928.

The stands on which jewelry is displayed in show-windows are commonly made of material covered by perishable fabric which is easily affected by sunlight and dust, and must be renewed from time to time which entails considerable expense.

The object of the present invention is to provide a stand or support for displaying jewelry in show-windows in which the perishable part is reduced to a minimum.

To this end the support according to the present invention consists of a glass-plate provided with one or more narrow oblong openings, and a corresponding number of sheaths made of a yielding material which is covered with a suitable fabric for instance velvet. A piece of jewelry such as a ring, bracelet or the like is inserted into each of these sheaths which are thereupon introduced into openings or slits in the said glass-plate. The sheaths thrust through the openings of the glass-plate on the one end display the jewels, whilst they support with the other end the glass-plate at an angle which can be obviously varied by varying the dimensions of the sheaths or the relation between the lengths of their two protruding ends. In the stands according to the present invention it suffices to renew from time to time the sheaths.

Two examples of a stand according to the invention are illustrated on the drawing. Fig. 1 shows the complete stand in a vertical

section, Figs. 2 and 3 the glass-plate in plan, Figs. 4 and 5 a sheath in two elevations. 35

The support consists of a glass-plate 1 which is provided with a horizontal opening 2, or with two or more parallel vertical openings 3, into each of which a sheath 4 holding a piece of jewelry such as ring 5 can be inserted. 40

The plate 1 can have of course any desired shape or colour, and it can be made of any durable material which does not suffer from exposure to sun-light, dust and damp. Likewise the number and position of the openings is not limited. 45

I claim:

1. A display device for jewelry comprising a plate having a slot, and a sheath retained in said slot extending beyond both sides of said plate, the lower end serving as a support for said plate and the upper end having an opening for receiving said jewelry, said sheath being slidably adjustable in said slot. 55

2. A display device for jewelry comprising a plate having a slot, and a sheath frictionally retained in said slot extending beyond both sides of said plate, the lower end serving as a support for said plate and the upper end having an opening for receiving said jewelry, said sheath being slidably adjustable in said slot. 60

In testimony whereof I affix my signature.

ARNOŠT FISCHMANN.
